UNITED STATES PATENT OFFICE

111,288

DESIGN FOR A DIAPER

John R. Lankenau, Brighton, Mass.

Application June 14, 1938, Serial No. 77,828

Term of patent 14 years

To all whom it may concern:

Be it known that I, John R. Lankenau, a citizen of the United States, residing at Brighton, county of Suffolk, and State of Massachusetts, have invented a new, original, and ornamental Design for a Diaper, of which the following is a specification, reference being had to the accompanying drawing, forming a part thereof.

Fig. 1 is a view looking at the outer face of the diaper in its outspread position;

Fig. 2 is a similar view looking at the inner face of the diaper; and

Fig. 3 is a front view showing the diaper as it appears upon the wearer.

The dominant feature of my design resides in the combination on a diaper of the contour shown of the ties, button and buttonholes, as shown.

I claim:

The ornamental design for a diaper, substantially as shown and described.

JOHN R. LANKEAU.
